Patented Nov. 4, 1924.

UNITED STATES PATENT OFFICE.

TAUBE DAVIS, OF NEW YORK, N. Y., ASSIGNOR TO FRANKLIN SIMON & CO., INC., OF
NEW YORK, N. Y., A CORPORATION OF NEW YORK.

DESIGN FOR A COAT.

Application filed July 24, 1924. Serial No. 10,249. Term of patent 8½ years.

To all whom it may concern:

Be it known that I, TAUBE DAVIS, a citizen of the United States, and a resident of the city of New York, borough of Manhattan, in the county and State of New York, have invented a new, original, and ornamental Design for Coat, of which the following is a specification, reference being had to the accompanying drawing, forming part thereof, wherein the coat is distinguished by means of the fur lining effect caused by the arrangement of fur cuffs, collar, and front edge members extending over the edges in both directions and an appreciable distance over the inside of the coat.

The design is also distinguished by the ar-

rangement of stripes or groups of pieces of fur on the front trimming edges, collar and cuffs, the group arrangement being carried throughout.

In the accompanying drawing—

Figure 1 is a front view of a coat, showing my improved design, the coat being illustrated closed.

Figure 2 is a view similar to Figure 1 with the front of the coat open and thrown back partially.

I claim:

The ornamental design for a coat, substantially as shown and described.

TAUBE DAVIS.
